DOUBLET & CIE., OF LEVALLOIS-PERRET, SEINE, FRANCE.

MAGNETO-ARMATURE.

1,394,289.

Specification of Letters Patent.

Patented Oct. 18, 1921.

Application filed March 30, 1921. Serial No. 457,112.

(GRANTED UNDER THE PROVISIONS OF THE ACT OF MARCH 3, 1921, 41 STAT. L., 1313.)

To all whom it may concern:

Be it known that I, MAURICE DUTEN, citizen of the Republic of France, and resident of Levallois-Perret, Seine, France, (post-office address, 54 Rue des Arts,) have invented new and useful Improvements in or Relating to Magneto-Armatures, (for which I have filed an application in France, February 25, 1920, Patent No. 510,725,) which improvements are fully set forth in the following specification.

This invention relates to armatures for magnetos and is characterized by a method of making the said armature in three parts, namely two steel end pieces and a core made of soft sheet-metal engaging the said pieces.

The subject-matter of the invention is illustrated in the accompanying drawings in which—

20 Figure 1 is a side elevation.

Fig. 2 a horizontal section on line A—A of Fig. 1, and

Fig. 3 is an end elevation.

The steel end pieces *a*, of usual shape, are of unitary construction and are provided each with a central opening *b* adapted to receive one end of the core *c* constituted by a plurality of soft sheet-metal elements *d* packed between two clamping cheek plates *e* made of steel. Rivets *f* form the said cheek plates and laminated elements into a compact and rigid bundle, the ends *g* of which have a shape conforming generally to that

of the openings *b* in the end pieces *a* and are driven through said openings so as to have 35 a forced fit therein. The said ends *g* are slightly mortised, as shown, thereby providing shoulders against which the end pieces abut.

A magneto armature made according to 40 the present invention is very strong since the core is the only riveted part which however is strengthened owing to its ends firmly engaging the end pieces.

I claim as my invention:—

45 A rotor member, comprising a pair of steel end pieces each provided with an opening; and a core consisting of a plurality of soft-metal laminæ, a pair of cheek plates between which said laminæ are packed, and 50 rivets extending through said cheek plates and laminæ to form the same into a compact rigid bundle; said core having mortised ends which are shaped to conform generally to the shape of the openings in the end pieces and are in intimate contact with the walls of said openings, said end pieces abutting against the shoulders produced by the mortised formation of the core ends.

55 In testimony whereof I have signed this 60 specification in the presence of two subscribing witnesses.

MAURICE DUTEN.
